UNITED STATES PATENT OFFICE.

TONY KLIPPEL, OF FRANKFORT, INDIANA.

DESIGN FOR A TOY LOCOMOTIVE.

55,567.

Specification for Design.

Patented June 29, 1920.

Application filed March 18, 1920. Serial No. 366,991. Term of patent 14 years.

To all whom it may concern:

Be it known that I, TONY KLIPPEL, a citizen of the United States, residing at Frankfort, in the county of Clinton and State of Indiana, have invented a new, original, and ornamental Design for Toy Locomotives, of which the following is a specification, reference being had to the accompanying drawing, forming part thereof.

The single figure of the drawing is a

perspective view, taken from the side, of a toy locomotive, showing my new design.

I claim as my invention:

The ornamental design for a toy locomotive, as shown.

In witness whereof I have hereunto set my hand at Frankfort, Indiana, this 15th day of March, A. D. one thousand nine hundred and twenty.

TONY KLIPPEL.
